UNITED STATES PATENT OFFICE.

EDWARD PEEL STEVENSON, OF GERRARDS CROSS, BUCKINGHAMSHIRE, ENGLAND.

LOCOMOTIVE.

Application filed February 24, 1927, Serial No. 170,643, and in Great Britain February 20, 1928.

This invention relates to locomotives having furnaces using pulverulent fuel.

The use of pulverized fuel has manifest advantages in certain circumstances and in countries where large quantities of low grade coal are available pulverized coal is largely used for stationary furnaces. Its use, however, for locomotives is limited because of the difficulty of storing and transporting the pulverized material.

10 The present invention consists in providing on a locomotive having a furnace using pulverulent fuel a fuel pulverizing mill either on the locomotive proper or its tender.

15 Facilities which may comprise automatic devices are provided for feeding the fuel from the tender to the mill and for feeding the pulverized fuel from the mill directly to the furnace or to a feeding device therefor.

20 One or more power fans, ejector devices or mechanical conveyors may be provided on the locomotive for blowing the pulverized fuel from the mill or mills to the furnace of the boiler.

25 Power for operating the pulverizing mill and fuel feeding device may be obtained from the locomotive, or from a petrol motor or other independent source so that during normal running such power may be obtained from the locomotive, and the petrol or other auxiliary motor used for driving the mill when there is no steam in the boiler.

30 When fans are used for blowing the pulverized fuel to the furnace, the furnace may be fitted with atmospheric burners and the air supply thereto obtained from the fan by a separate pipe. Also the air supply to the pulverizer may be heated by passing it through pipes or chambers adjacent the furnace.

35 The invention is illustrated more or less diagrammatically by the accompanying drawings, wherein:

40 Figure 1 is an elevation of a sufficient portion of a locomotive to illustrate the invention.

Figure 2 is a corresponding plan and

45 Figure 3 a section through A—A of both of these figures.

Figures 4, 5 and 6 are corresponding views of a modified construction of the invention.

50 In these drawings 2 is the locomotive proper and 3 its tender. The tender 3 is provided with a fuel receptacle having in-

clined sides 3^a, 3^b, 3^c and 3^d leading to a trough 3^e in which extends the lower end of an endless conveyor 4, the upper end of the conveyor 4 being arranged to deliver fuel from the trough 3^e into a common feeding hopper 5^a of two pulverizing mills 5^b and 5^c driven by a turbine 6 connected by a steam pipe 6^a to the boiler, or the mills may be driven by a petrol motor 17^c.

55 The spaces 3^a beneath the inclined sides 3^b, 3^c and 3^d are utilized as water tanks.

60 The turbine 6 also drives a fan 7 for supplying air to atmospheric burners 8 through a pipe 9, the burners 8 being arranged in the rear wall of the furnace 13.

65 The pulverized fuel from the top of the mills 5^b and 5^c is discharged through pipes 10, 11 and 12 to the burners 8. One or more valves may be provided in the pipe system 10, 11, 12 for regulating the feed of the 70 pulverized fuel to the furnace 13.

75 The two pulverizing mills 5^b and 5^c are preferably provided with driving gear whereby they can be driven separately or together so that on a heavy load both mills 80 can be utilized, while should one become damaged or otherwise ineffective, the other mill will have sufficient capacity to deliver sufficient fuel to the furnace to permit of the satisfactory operation of the locomotive, 85 possibly at a reduced speed.

80 The discharge of the pulverized fuel from the mills 5^b and 5^c to the burners 8 is by means of the fan 7. The air to the mills 5^b and 5^c and fan 7 is heated by drawing in 90 through a casing or jacket 15 adjacent the walls of the furnace 13, and is drawn from the casing or jacket 15 through the pipes 16^a, 16^b, 17, 18^a and 18^b to the mills 5^c and 5^b.

95 In the modified construction of the invention illustrated by Figures 4, 5 and 6, the inclined sides 3^b, 3^c and 3^d of the tender 3 converge to a horizontal trough 3^e in which is arranged a spiral conveyor 4^a the front end of which discharges fuel into the lower end of a vertical spiral conveyor 4^b. From the top of the conveyor 4^b the fuel is discharged into a hopper 5^a arranged to discharge fuel as in the previous example into the pulverizing mills 5^b and 5^c. These mills 100 are driven by petrol motors 17^a and 17^b, or by turbines 6^a and 6^b which also drive fans 7^a and 7^b. In this example the fuel from the top of the pulverizing mills 5^b and 5^c is fed along pipes 10^a and 10^b to the front 110

end of a furnace feed conduit 8^a arranged to discharge fuel into the furnace 13. The feed conduit 8^a is provided at its front and rear ends with dampers 20 and 21.

5 The discharge from the pulverizer to the firebox may be by means of an injector device into the top or bottom of the firebox or by means of a screw or other feeding device as described for example, in the specification of British Letters Patent No. 109,063. Means will, of course be provided for ensuring and regulating an air supply to the furnace firebox sufficient to ensure satisfactory combustion and means may be provided 15 for regulating the supply of fuel to the pulverizer in accordance with the requirements of the furnace.

I claim—

1. A steam locomotive comprising a furnace using pulverulent fuel, a fuel pulverizing mill, means for conveying pulverized fuel from the mill to the furnace, and self contained means for driving the mill independently of the driving power of the locomotive.

2. A locomotive comprising a steam generator having a furnace using pulverulent fuel, a fuel pulverizing mill, means for conveying pulverized fuel from the mill to the furnace, and self contained means for driving the mill when there is no steam in the steam generator.

3. A steam locomotive comprising a furnace using pulverulent fuel, a fuel pulverizing mill, means for conveying pulverized fuel from the mill to the furnace, a motor for driving the mill, and power for driving the motor, the power for driving the motor being independent of that for driving the locomotive.

4. A steam locomotive comprising a furnace using pulverulent fuel, a fuel pulverizing mill, means for conveying pulverized fuel from the mill to the furnace and a petrol motor, the petrol motor being arranged to drive the mill.

5. A steam locomotive comprising a furnace using pulverulent fuel, a fuel pulverizing mill, means for conveying pulverized fuel from the mill to the furnace, a receptacle for unpulverized fuel, means for conveying the fuel from the base of the fuel receptacle upwards to the mill, and means for driving the mill independently of the driving power of the locomotive, the means for conveying the pulverulent fuel from the mill to the furnace being arranged to operate simultaneously with the means for driving the mill.

6. A steam locomotive comprising a furnace using pulverulent fuel, a fuel pulverizing mill, a fan for conveying pulverized fuel from the mill to the furnace, a receptacle for unpulverized fuel, means for conveying the fuel from the base of the fuel

receptacle upwards to the mill, a petrol motor, the petrol motor being arranged to drive the mill and also the fan.

7. A steam locomotive comprising a furnace using pulverulent fuel, a fuel pulverizing mill, a fan for conveying pulverized fuel from the mill to the furnace and means for driving the mill and the fan from the power of the locomotive as well as from power independent of the driving power of the locomotive.

8. A steam locomotive comprising a furnace using pulverulent fuel, a fuel pulverizing mill, a fan for conveying pulverized fuel from the mill to the furnace, a petrol motor, the petrol motor being arranged to drive the mill and the fan, and means for driving the mill and fan from the power of the locomotive.

9. A steam locomotive comprising a furnace using pulverulent fuel, two fuel pulverizing mills, and means comprising a fan for conveying pulverized fuel from the mills to the furnace, and means for driving the fan and for driving the mills independently of the driving power of the locomotive.

10. A steam locomotive comprising a furnace using pulverulent fuel, two fuel pulverizing mills, a fan arranged to convey pulverized fuel from the mills to the furnace, a petrol motor, the petrol motor being arranged to drive the fan and the mills, independently of the driving power of the locomotive.

11. A steam locomotive comprising a furnace using pulverulent fuel, two fuel pulverizing mills, a fan arranged to convey pulverized fuel from the mills to the furnace, a petrol motor, the petrol motor being arranged to drive the mills and the fan, and means for driving the mills and fan from the power of the locomotive.

12. A steam locomotive comprising a furnace using pulverulent fuel, a fuel pulverizing mill, a fan arranged to convey pulverized fuel from the mill to the furnace, a steam turbine, and a petrol motor, the petrol motor being arranged to drive the fan and the mill, and the turbine to drive the fan and the mill by using steam from the locomotive boiler.

13. A steam locomotive comprising a furnace having a burner for pulverulent fuel, a fuel pulverizing mill, a fan for conveying pulverized fuel from the mill to the furnace and a separate supply of air to the burner, and means for driving the mill and the fan from power independent of that used for driving the locomotive.

14. A steam locomotive comprising a furnace having a burner for pulverulent fuel, a fuel pulverizing mill, a fan for conveying pulverized fuel from the mill to the furnace and a separate supply of air to the burner, a petrol motor, and a steam turbine, the petrol

motor being arranged to drive the mill and the fan, and the turbine to drive the fan and the mill by using steam from the locomotive boiler.

5 15. A steam locomotive comprising a furnace using pulverulent fuel, a fuel pulverizing mill, a fan arranged to convey pulverized fuel from the mill to the furnace, a petrol motor, means for heating the air supply to the fan, the petrol motor being arranged to drive the fan.

16. A steam locomotive comprising a furnace using pulverulent fuel, a fuel pulverizing mill, a fan arranged to convey pulverized fuel from the mill to the furnace, means for driving the mill and fan, means for heating the supply of air to the fan and means for driving the mill and the fan from the power of the locomotive, the means for driving the mill and fan being independent of the driving power of the locomotive.

17. A steam locomotive comprising a furnace using pulverulent fuel, a fuel pulverizing mill, a fan arranged to convey pulverized fuel from the mill to the furnace, means for heating the supply of air to the fan, a steam turbine, and a petrol motor, the petrol motor being arranged to drive the fan and the mill and the turbine also to drive the fan and the mill using steam from the locomotive boiler.

30 18. A steam locomotive comprising a furnace having a burner for pulverulent fuel, a

fuel pulverizing mill, a fan for conveying heated air and pulverized fuel from the mill to the burner of the furnace, and a separate supply of heated air from the fan to the burner, means for heating the air supply to the fan, a petrol motor and a steam turbine, the petrol motor being arranged to drive the mill and fan, and the turbine to drive the fan and the mill by using steam from the locomotive boiler.

19. A steam locomotive comprising a furnace using pulverulent fuel, a fuel pulverizing mill, a fan for conveying pulverized fuel from the mill to the furnace, a receptacle for unpulverized fuel, an unpulverized fuel conveyor, and a petrol motor, the fuel receptacle being constructed with sloping sides leading to a trough at its base into which the conveyor extends and from which it rises to deliver fuel to the mill, the petrol motor being arranged to drive the mill and also the fan.

25 20. A steam locomotive comprising a furnace using pulverulent fuel, a fuel pulverizing mill, a fan arranged to convey pulverized fuel from the mill to the furnace, a petrol motor, and a pipe for delivering air and pulverized fuel from the mill to the fan end of the furnace, the petrol motor being arranged to drive the fan and the mill independently of the driving power of the locomotive.

In witness whereof I affix my signature.

EDWARD PEEL STEVENSON.
